Application February 19, 1931, Serial No. 516,977

42 Claims. (CL 276—21)

The general object of this invention is to provide a machine adapted to compose numeral type on a printing member by the actuation of a computing machine, so that a printing form may be made which automatically corresponds to the amounts added on the computing machine.

More particularly, it is an object of the invention to combine a so-called billing machine having a keyboard actuated computing mechanism with a mechanism for assembling individual type in a line channel, with the result that as billing machine keys are actuated to add certain amounts, there is a corresponding actuation of the typesetting unit to set up the same numerals in a row, ready for subsequent use in printing any desired number of copies of the same matter.

Another object of the invention is to provide a simple, readily attachable, intermediate mechanism adapted for actuation by a standard billing machine to effect operation of a standard typesetting machine.

Another object is to provide a manual mechanism adapted by one actuation to cause the assemblage of a definite number of type in the typesetting machine, as for instance, a number of space quads, thus avoiding the necessity of a number of successive actuations of a key or space bar. By this means, we are able to fill out the column with spaces at the left of the significant figures to cause such figures to be in proper column alignment in successive lines.

Another feature of the invention is to so combine the billing machine with a keyboard operated typesetting machine so as not to interfere with the operation of the typesetting machine by its own keyboard.

Billing machines having computing and typewriting mechanisms are sometimes equipped, in the typewriting portion, with a ribbon-shift to enable the writing of deficits or similar amounts in red, and it is one of the objects of our invention to cause some corresponding indication in the line of set type. We effect this by coupling the ribbon-shift mechanism with means for setting an indicating type (for instance, an asterisk) with the row of figure type, so as to enable the printed column to disclose at a glance what figures are printed in red on the typewritten portion of the billing machine.

Our invention comprises the means by which we accomplish the above operations, or any of them. It includes, also, various other features hereinafter more fully explained contributing to the efficiency of the operation or the simplicity of the mechanism.

While our invention is not limited to the employment of any particular billing machine or any particular typesetting machine, we have found very effective, for our purpose, the billing machine known as the "Moon-Hopkins", set out in detail in Patent No. 1,336,904 to Hubert Hopkins, and also in Patents No. 1,366,566 to Hubert Hopkins and No. 1,317,604 to Otto Thieme, and as the typesetting machine we have effectively employed the machine known as the "Set-O-Type" made in accordance with Patents Nos. 1,686,031, 1,675,050 and 1,672,953 to F. H. Poepelmeier.

The drawings illustrate such Moon-Hopkins billing machine and such Set-O-Type in sufficient detail to show the connection with our intermediate mechanism. Reference is made however to the patents mentioned for further details of the billing machine and typesetting machine.

In the drawings, Fig. 1 is a perspective of a complete machine in accordance with this invention; Fig. 2 is a side elevation of the typewriting and computing portion of the machine; Fig. 3 is an enlarged side elevation of a portion of a typewriting machine, showing the ribbon shifting mechanism and the means for causing a corresponding operation of the typesetting machine; Fig. 4 is a perspective of the circuit closing machine operated by certain of the keys of the computing unit; Fig. 5 is a plan of a portion of the keyboard of the computing machine with our attached actuator for the typesetting machine; Fig. 6 is a vertical section through the computer keyboard and the attached typesetter actuator, as indicated by the line 6—6 in Fig. 5; Fig. 7 is a section on the line 7—7 of Fig. 6 through that portion of the typesetter actuator which releases a succession of quads; Fig. 8 is a diagram of the electric circuits connecting the various mechanisms; Fig. 9 is a vertical section through the typesetting machine in a plane at substantially right angles to that general plane of the typesetting machine shown in Fig. 1, this view illustrating also the electric circuits for actuation by the billing machine keyboard or the typesetting machine keyboard as desired.

The Moon Hopkins billing machine is adapted for various computations, additions, multiplications, subtractions, divisions, etc., but we are concerned primarily with its employment as an adding machine. As illustrated in Figs. 1, 2 and 5, there is provided in the Moon-Hopkins machine a group of numeral keys distinct from the numeral keys of the typewriter machine itself, which group of keys operate the computing ma-

chine and may likewise cause printing on the typewriter cylinder. This leaves the ordinary numeral keys of the typewriter keyboard free for typing without affecting the computing machine. The distinct numeral keys of the billing machine with which our invention is concerned comprise ten keys (one for each digit) arranged in the group A, Fig. 5, and these keys we have coupled with the typesetting machine as herein-
10 after explained.

In operating the Moon-Hopkins machine for adding purposes, the operator strikes any of the ten numeral keys comprised in the group A in the order in which the figures occur in the line
5 to be introduced into the machine. These keys, through mechanism indicated at B, set mechanism in the computor designated generically C. When these keys have been struck for all of the digits in the line, a key, for instance that designated E, is depressed, which actuates a motor to place the number indicated by the depressed keys in the rear totalizer of the machine. This same operation is repeated for the different numbers.
20 Eventually a total may be taken by actuating the totalizer key F, which, through the motor, transfers the accumulated total from the rear totalizer to the forward totalizer and causes special type-bar mechanism to coat with the platen cylinder D to print the total thereon.

25 As an illustration, if the first number were "123" the operator would strike the 1 key, the 2 key and the 3 key in this order, and then depressed the E key to place the number in the rear totalizer. If the second number were "456" he would then strike the 4 key, the 5 key and the 6 key in order and depress the E key to add this number to the preceding number on the rear totalizer, so that the latter would stand at "579". Now, if the totalizer key F is depressed,
40 this effects the printing of the numeral "579" on the platen B of the typewriter unit by means of special printing members.

The Set-O-Type machine comprises two active banks of type cases M, one behind the other, in which the individual type, which are short members grooved on their opposite sides, are contained in upright channels side by side. These channels are curved outward at their lower ends, as shown in Fig. 9, so that the type come down
45 against a suitable abutment opposite the end of the curved path. The endmost type is supported by friction between the abutment and the remainder of the line of type, and is ejected whenever desired by the downward action of the inner end of a rocking lever N—one for each type channel. Each of these levers is actuated by the upward movement of a corresponding plunger P acting as the core of a solenoid Q. The ejected type slides down a twisted tube R forming part
50 of a triangular race plate S. It is thus brought to the control of an ejecting unit T which operates automatically to shove the bottommost type forward into a channel of a multigraph segment U, the rails of which occupy the grooves of the type.
55

When the proper number of type have been assembled in the multigraph segment, the same is indexed by a suitable mechanism designated V to bring a new line into registration with the ejection mechanism. Later, when the whole form
60 has thus been set up on the multigraph segment, it is removed from the Set-O-Type and transferred to an ordinary multigraph printing machine.

75 The Set-O-Type machine is ordinarily actu-

ated from a keyboard W, the keys of which close circuits in a cable W1 leading to the respective solenoids Q, with the result that when a key is depressed, the corresponding type is discharged and is delivered to the receiving segment.

Our intermediate mechanism provides an attachment for the Moon-Hopkins billing machine adapted to coat with the numeral keys in group A thereof, and be operated thereby to close circuits which are coupled, in parallel with the circuits of the keyboard W, with the respective solenoids of the Set-O-Type. In other words, the conductors from the various solenoids Q which control the ten channels having the ten digits, divide and pass equally to the numeral keys of the Set-O-Type keyboard W and to the circuit closers actuated by the ten keys of the group A of the billing machine. We have found it very convenient to attach the branch circuits from the billing machine at the keyboard W so that the original connections from this keyboard to the typesetting machine, grouped in the cable W, need not be disturbed.

The frame of our attachment to the billing machine comprises a suitable shallow insulating box 10 adapted to extend beneath the front portion of the frame of the Moon-Hopkins machine and be clamped thereto. As shown more particularly in Fig. 6, this box 10 comprises a bottom plate, a top plate 12 and suitable cross filling strips 13. We have mounted in the interior of this box, along the front and rear thereof, a pair of insulating strip carrying pairs of contacts, the contacts of each pair being normally out of engagement with each other. One of such strips 15 and one pair of such contacts 20, 21 are shown in Fig. 4. The upper contact of each pair is directly beneath a suitable plunger 23 which stands beneath the corresponding numeral key of the A group.

100 Preferably the forward insulation bar 15 carries five pairs of rearwardly extending contacts coacting with the forward five keys of the A group of the billing machine, and the rear bar carries five pairs of forwardly extending contacts coacting with the rear five keys. If, for instance, the five keys in the A group of the billing machine are for numerals 1, 3, 5, 7 and 9, these five pairs of contacts are carried by an insulating bar 15 along the front portion of the box 10. Then the second row of Moon-Hopkins keys, corresponding to the designation 0, 2, 4, 6 and 8 coat with forwardly extending contacts carried by a rear bar 15 in the box.

105 In any case, there is a plunger 23 over a pair of contacts and directly beneath the numeral key of the Moon-Hopkins machine, so that whenever any one of those keys is depressed, a corresponding pair of contacts 20, 21 are closed, thus actuating the corresponding solenoid of the typesetting machine and causing the corresponding type to be set on the multigraph segment.

110 In order that the numerals set in successive lines in the multigraph segment shall be in proper column order irrespective of the length of the 140 numeral, we set in the multigraph channel, by the Set-O-Type, a number of quads corresponding to the amount that the particular numeral is short of the maximum. For instance, if the numerals all run less than 1,000,000, a maximum space is to be provided for six digits; then, if the numeral to be struck was for instance "2513", one would place in the multigraph segment two spaces preceding the numeral. If the numeral were "57" one would place four spaces preceding 150

it, and so on, with the result that the last digit struck in a line always comes in a unit space.

The assemblage of the space quads might be accomplished by operating a space key a certain number of times, for instance twice in the case of the numeral "2513" and four times in the case of the numeral 57, but to expedite the operation, we provide a manual device which, by a single actuation, will cause the ejection of the desired number of quads in the Set-O-Type. This manual device may operate on the principle of a telephone dial, the operator placing his finger in any particular opening, then turning the dial until his finger reaches the guard, and then allowing the dial to return to normal position. This makes a number of successive contacts corresponding to the numeral designation of the dial hole in which the operator placed his finger, and these contacts cause successive impulses of the quad-releasing solenoid of the Set-O-Type, resulting immediately in that number of quads being assembled on the multigraph segment.

The dialing provision is a very valuable feature, not only in saving time, but in insuring accuracy of the number of quads delivered, which gives accuracy in the alignment of the figures on the multigraph segment. For instance, if seven blank spaces are required before the significant figures, there is less liability of error when the operator simply places his finger in the opening designated "7" and operates the dial in the usual telephone manner, than where he gives seven successive actuations to a key. This dial mechanism will now be described.

The dial mechanism shown in Figs. 5, 6, 7 and 8 comprises a stationary stud 30 carried by an insulated base plate 31 secured to the top of the box 10; a revolute stud 32 having a central bore embracing a reduced extension of the stationary stud; a disk 35 rigidly secured to the rotatable stud and having ten finger openings 36 adjacent its periphery; a casing 37 having a top plate 38 with an arcuate row of numerals below the openings 36 and carrying a stop guard 39 overhanging the disk 35 and serving to limit the finger rotation thereof.

Within the dial casing 37 is a disk 40 having on its periphery ten or more equally spaced projections 41, this disk being pinned rigidly to the rotary stud 32. This disk coats with a pawl 43 pivotally mounted on a movable contact spring 44 and held in normal position by a spring 45. The pawl is so mounted, that when the dial is turned by the operator's finger in the right hand direction, the corresponding teeth 41 successively push back the pawl 43 so that it has no effect. Mounted about the stud 32 is a spiral spring 46 anchored at one end to the hub of the disk 40 and at the other end to the inner periphery of a stationary cup 47 which is secured to the top 38 of the casing. This spring therefore is wound up as the dial is turned in the right hand direction, and operates to return the dial when released, and in such return, every time a tooth 41 engages the pawl 43, it swings the contact spring 44 against a fixed contact 48 and thus closes the circuit. Accordingly, the circuit is successively closed a number of times, corresponding to the numeral in which the operator's finger was inserted in turning the dial 35 from its normal position to the position where the operator's finger engages the guard 39.

To prevent undue speed of the return of the toothed disk 40 of the dial, a suitable friction brake is provided. This is shown as comprising

a wheel 50 connected by gearing 51, 52 with the revolute stud 32, a suitable brake shoe 55 coacting with the periphery of the disk. This brake shoe is shown as mounted on a leaf spring 56 adjusted by a screw 57.

The dialing mechanism which is very similar to the familiar one on a telephone, is conveniently located adjacent the right hand edge of the numeral keyboard of the Moon-Hopkins machine, and may be readily actuated by the operator thereof to cause the desired number of quad spaces to be set up in the multigraph segment in the typesetting machine.

In addition to the setting of numeral type in the segment, it is convenient to set type for printing various signs, as for example, a period to space the cents, a dollar sign, and an asterisk to indicate negative amounts. We have provided three special keys for setting such type. These keys are indicated at 61, 62 and 63 in Figs. 5 and 6 and are preferably located in a transverse row between the right hand edge of the Moon-Hopkins machine and our dialing mechanism. These keys operate contacts, which may be similar to those shown in Fig. 4, from which contact circuits extend to the Set-O-Type in a similar manner to those of the numeral keys.

The Moon-Hopkins billing machine is provided with a ribbon shift to enable the printing of negative amounts in red. This ribbon shift is indicated in Figs. 2 and 3 as a shiftable spool G connected by a link with a lever H, the other end of which carries a finger key I. A suitable spring J may be used to maintain the ribbon normally in the position for printing in black.

Now, in our invention, we provide the asterisk circuit with a divided branch which has an additional closure operable by the ribbon shift key I. This is illustrated in Fig. 3, where a suitable casting 70 is shown having a plunger 71 directly behind the key I, this plunger operating to force a movable contact 72 against a fixed contact 73, similar to those shown in Fig. 4, carried by an insulating support 75 in the casing. The two circuit wires leading from the contacts 72 and 73 joint those contacts from the asterisk key 63, with the result that asterisks can be set up whenever desired by the key 63, or may be manually set whenever the billing machine key I is shoved in to shift the ribbon.

As the Moon-Hopkins billing machine operates on the principle of accumulating the amount in the adding mechanism and thereafter causing the printing of the figures struck by the operation of a motor energized by an operating key E, it follows that if the operator actuates the key I after the number has been struck and before the operating key is struck, the imprint on the platen of the billing machine will be in red and an asterisk will appear on the multigraph segment following the numeral struck. As the numerals in successive lines in the multigraph segment terminate in the same unit position, the asterisks, whenever they appear, will stand at the right of the unit column and be readily observable on the printed copy.

We will now trace the electric circuits as shown in Fig. 3. The various circuits from the contacts w1, w2, w3 for the numeral keys, the sign keys, and the space bar of the Set-O-Type keyboard are in the Set-O-Type machine carried in a cable W1 from the keyboard W to the various solenoids Q. These circuits for the ten numerals are indicated in the diagram collectively by W1. The circuits we have added are branches of the 159

Set-O-Type circuits and are carried in a cable 80 leading from the attachment 10 to the Set-O-Type keyboard. There is one individual conductor from one contact of each pair 20, 21 and a 5 common return for all of the pairs, these contacts constituting the X-group in the diagram.

Referring to the contacts for the 0, 2, 4, 6, 8 key 85 of the billing machine, there are individual lines 81, 82, 83, 84 and 85 which join respectively the 10 lines from the 0, 2, 4, 6, 8 of the Set-O-Type keyboard contacts w_1 of the solenoids. There are likewise five other individual lines leading from the contacts 20, 21 corresponding to the front row of keys 1, 3, 5, 7, 9 of the billing machine to the 15 corresponding Set-O-Type contacts w_1 . The common return line 86 from all of the X-group of contacts for the billing machine joins the common return w from the Set-O-Type contacts w_1 and leads through a suitable source of power O 20 to the line w_4 to all of the solenoids Q in parallel.

Connected to the branch return 87 is a common 25 return 88 for the Y-set of contacts relating to the sign keys 61, 62, 63. Individual lines y lead from these contacts to the individual lines of the Set-O-Type system W1. The sign contacts w_2 of the Set-O-Type lead by individual lines w_5 to the corresponding solenoids and the common return w_6 leads to the return w . It is to these individual lines w_5 that the individual lines y of the Y set 30 are connected.

Another branch of the common return 87 leads to the terminal 44 of the Z unit, that is, the dial system. From the other terminal 48 of this Z-group, a line 89 continues to a junction with the 35 Set-O-Type line w_7 which comes from the space bar contacts w_3 of the Set-O-Type keyboard. The return line from the space bar contacts w_3 is designated w_8 and leads to the return w . Accordingly, the actuation of the space bar or of the dial 40 actuates that one of the solenoids Q which releases the space squads, this being the solenoid designated q in Fig. 8.

It will be seen from the tracing of the diagram 45 that all the circuits provided by us, whether closed by the numeral keys of the billing machine, or by the special keys 61, 62, 63, or by the actuation of the dial, are all in parallel with the corresponding circuits which already exist from the Set-O-Type keyboard to the Set-O-Type solenoids. This is further illustrated in Fig. 9 where 50 illustrative keys are shown of the A-group in the billing machine and of the W1-group of the Set-O-Type.

By making our connection from the Moon-Hopkins machine in parallel with the connections from the Set-O-Type keyboard, it is apparent that they need not in any manner interfere with the normal operation of that keyboard. The Set-O-Type keyboard may be used for instance 55 to set up in type, words and figures in the body of a form corresponding to the words and figures in a copy to be printed on the typewriter cylinder D by the ordinary typewriter keys. If desired, such form may be typed in advance on the Set-O-Type keyboard so that the words and non-computing figures of the form will be mounted on the multigraph segment as they are to appear in the typewritten copy. Thereafter, when the coupled 60 numeral keys are struck, the addition is made on the computing machine and the same numerals are caused to be printed on the typewriter platen D and set up in the form of type in the multigraph segment. At the end of the computation, the 65 striking of the totalizer key will produce the total 70 and print it on the typewriter platen. The opera-

tor may then repeat this total by means of the numeral keys of the Set-O-Type, which will thus set up the corresponding total in type on the multigraph segment; or, in place of striking the total on the type-setter keyboard, one may use the billing machine numeral keys just as if the amount were to be added, and then, by operating the error key of the billing machine, clear that amount from the computing mechanism.

It should be observed that our attachment is very simple in construction and easily applied to existing machines, without requiring any alterations thereof, and when applied, it is out of the way and does not interfere in any manner with the ordinary operation of the machine. When however keys of the computing machine are struck which are to add figures on the computer, the result is an automatic setting of the same figures in the printing member. This increases the speed over that required to operate a keyboard or keyboards successively for the different numbers, and has the very pronounced advantage of insuring absolute correspondence of the figures added on the machine and the figures set in the printing form, and finally, due to our dialing system, the proper columnation of the successive items is effected in the minimum time.

We claim:

1. The combination of a computing machine equipped with numeral keys, a typesetting machine and means whereby the numeral keys which actuate the computing machine may also assemble the corresponding type in the typesetting machine.

2. The combination with a computing machine having numeral keys to actuate it, a typesetting machine having a type case, mechanism for ejecting type therefrom and assembling it, and connecting mechanism between each of said numeral keys of the computing machine and the ejecting mechanism for the corresponding numeral in the typesetting machine.

3. The combination of a computing machine having numeral keys to actuate it, a composing machine having individual electrically operated elements corresponding to the different digit type, and a set of contacts in the computing machine actuated by the numeral keys thereof and controlling said elements.

4. The combination of a computing machine having numeral keys to actuate it, a typesetting machine having channels for individual type, and individual magnets and mechanism operated thereby for releasing type in any desired channel, a set of contacts actuated by said numeral keys of the computing machine, and electric conductors between said contacts and the corresponding magnets of the typesetting machine.

5. The combination of a computing machine having numeral keys to actuate it, a composing machine, a printing member, and means whereby the operation of the computing machine may cause the formation of a row of numerals on the printing member, said numerals corresponding to the actuated numeral keys.

6. The combination of a computing machine, a typesetting machine, a multigraph segment, and suitable connections whereby the operation of the computing machine causes the assemblage of type on the multigraph segment.

7. The combination of a computing machine, a typesetting machine having channels for short type grooved on their opposite sides, a member suitable for use in a printing machine and having parallel rails with overhanging edges adapted

- to confine rows of such grooved type, and suitable connections whereby the operation of the computing machine causes the assemblage of such type in such printing member.
5. 8. The combination of a composing machine having a keyboard including numerals, a computing machine having a numeral keyboard, mechanism for assembling printing characters in the composing machine connected jointly with 85 numeral keys of the composing keyboard and with numeral keys of the computer keyboard, whereby type may be assembled from either keyboard without regard to the other keyboard.
9. The combination of a typesetting machine, 13 having channels for individual type and having a keyboard including numerals, a computing machine of the character in which the digits are struck in the order which such digits occupy in the numerals, and mechanism for assembling 20 individual type in the typesetting machine connected jointly with numeral keys of the typesetter keyboard and with numeral keys of the computer.
10. The combination of a type case having provision for holding individual type, mechanism 25 for assembling type therefrom, two keyboards, either of which is adapted to cooperate said mechanism without regard to the other.
11. The combination of a case adapted to carry short individual type grooved on its opposite sides, 30 electrically actuated mechanism for discharging such type from any channel and assembling the same in a grooved removably mounted printing member, a keyboard electrically connected with said electric actuating mechanism, a computing machine having numeral keys, and electric connections from said numeral keys to the same electric actuators for numeral type on the typesetting machine.
- 40 12. The combination, with a composing machine and a computing machine, of an attachment for the computing machine comprising a frame carrying a set of contacts adapted to be closed by the actuation of numeral keys of the computing machine, and electric circuits leading from said contacts to electric actuators in the composing machine.
13. The combination with a computing machine, a frame adapted to be secured beneath the keyboard thereof, said frame carrying pairs of 50 electric contacts, one for each numeral key of the pertinent set of the computing machine, a composing machine having individual electro-magnetic actuators corresponding to different numeral type, and electric conductors leading from the contacts on the attached frame to the composing machine.
- 60 14. The combination of a composing machine, electric actuating mechanism therefor, and a manual device adapted to cause automatically a series of makes and breaks of the same circuit to the same electric actuator for one operation of the manual device.
- 65 15. The combination with an electrically actuated typesetting machine adapted to set up one type character for each actuation, and a manual device adapted, for each operation, to cause a succession of actuations of the same mechanism of the same typesetting machine.
- 70 16. The combination of an electrically actuated composing machine, a manual dial adapted when turned from normal position and returned to make a series of contacts, and conductors from said dial to the electric actuator of the composing machine.
17. The combination of a composing machine having an electric actuator, a dial having finger openings and a spring return, and means whereby the returning dial closes a number of contacts corresponding to the number of the opening in which the operator's finger is inserted, and a pair of conductors connecting said contacts with said electro-magnetic actuator of the composing machine.
18. The combination of a typesetting machine carrying space quads, an electro-magnetic device for assembling the same, a multiple circuit-closure adapted by one operation to make a succession of contacts, and electric connections between such multiple circuit closure and the electro-magnetic device of the typesetting machine.
19. The combination of a typesetting machine having a case containing space quads, a printing member, electro-magnetic mechanism for releasing the space quads one after the other, means for assembling the same on a printing member, a dial having a series of finger holes corresponding to the different digits and a spring return, and means whereby the turning of the dial to a definite position and allowing it to return to normal position makes a series of contact closures corresponding to the hole in which the finger was inserted, and electric connections from the dial to the magnet which releases the space quads.
20. The combination of a computing machine 105 having a keyboard, a frame secured to the underside of the keyboard and extending at one side thereof, a composing machine having numeral type and spaces, electric contacts carried by said frame in positions to be actuated by the numeral keys of the computer keyboard, a multiple circuit closure carried by said frame beyond the keyboard, electric connections from the contacts actuated by the numeral keys to the numeral magnets of the computing machine, and electric connections from the multiple closure mechanism to the space mechanism of the computing machine.
- 110 21. The combination of a typesetting machine having individual channels for numeral type and space quads, individual electro-magnets for releasing the same, mechanism for assembling the released type and quads on a member adapted for mounting in a printing press, a computing machine having numeral keys, a frame adapted to be secured thereto and having contacts adapted to be closed by the numeral keys and having a dial mechanism adapted to make such number of closures as desired, and electric connections between the contacts of such attached frame and the releasing magnets for the typesetter numerals, 115 and electric connections between the dialing mechanism and the releasing magnet for the typesetter quads.
- 120 22. The combination of a composing machine, 125 a computing machine, mechanism connecting numeral keys of the composing machine with the computing machine to cause the assemblage of corresponding numerals when the computing machine is actuated, and an extra key carried adjacent the computing machine and connected with the composing machine to set up a suitable indicating member associated with the numerals.
- 130 23. The combination of a computing machine 140 having a keyboard, an electrically actuated typesetting machine, carrying individual printing type, a frame adapted to be attached to the computing machine having a set of contacts operable by numeral keys of the computing machine, elec- 145
- 150

tric connections between said contacts and individual electric actuators in the typesetting machine adapted to release individual numeral type, an additional key carried by said frame, and electric connections between such key and an actuator on the typesetting machine for releasing suitable indicating type adapted to be assembled in line with the released numeral type.

24. The combination of a computing machine having a keyboard, a frame adapted to be attached to the underside of the keyboard and projecting beyond the same, contacts carried by the frame beneath numeral keys of the keyboard and adapted to be closed thereby, one or more extra keys carried by said frame beyond the computing machine keyboard, a dialing mechanism carried by said frame beyond the computing machine keyboard, a composing machine having electrically actuated mechanism for assembling numeral characters and sign characters and spaces, and electric connections between the computing machine numeral keys and the numeral actuators of the composing machine, and between the extra keys and sign character actuators of the composing machine, and between the dialing mechanism and the space mechanism of the composing machine.

25. The combination of a computing machine having a numeral keyboard, a typesetting machine having type channels, electro-magnetic mechanism for releasing type therefrom, mechanism for assembling the released type, means for removably holding a multigraph segment in position so that the type may be assembled thereon, means for indexing said segment to allow the assemblage in different lines, a frame adapted to be attached to the computing machine having a series of contacts beneath the numeral keys and adapted to be closed thereby and carrying a dialing mechanism beyond the keyboard, which dialing mechanism, when actuated, makes a variable number of contacts, as desired, and electric circuits between the different contacts for the numeral keys and the corresponding electric actuators for numerals of the typesetting mechanism, and conductors connecting the dialing mechanism with the space-quad releasing actuator of the typesetting machine.

26. The combination of a computing machine, a typewriting mechanism, a ribbon shift for the typewriting mechanism, an assemblage mechanism, connections between numeral keys of the computing mechanism and numeral actuators of the assemblage mechanism, and a connection between the ribbon shift with the typewriting mechanism and an actuator for an indicating member of the composing mechanism.

27. The combination of a billing machine having computing mechanism and a typewriting mechanism, means whereby figures corresponding to the numeral type may be automatically typed on the typewriting mechanism through a ribbon, a ribbon shift adapted to vary the color of impression, a composing machine, operating connections between computing numeral keys of the billing machine and numeral assemblage mechanism of the composing machine, and an operative connection between the ribbon shift of the billing machine and sign producing mechanism of the composing machine.

28. The combination of a billing machine having computing mechanism, numeral keys therefor, a typewriting machine having a platen and

a keyboard and mechanism operated thereby for writing on the platen, there being also mechanism for automatically writing on the platen figures of the computing machine, said writing on the platen being through a shiftable multi-colored ribbon, a typesetting machine having a series of channels carrying numerals and a channel carrying certain signs, individual electromagnetic mechanism for releasing type from the different channels, means for assembling them in a row, electric connections between the numeral keys of the computing machine and the individual numeral releasers of the typesetting machine, and an electric connection between the ribbon shift of the typewriting machine and the mechanism for assembling said special sign into the same row.

29. The combination of a typewriting machine having a ribbon shift, a composing machine, and mechanism adapted to cause the presentation of a special character in the composing machine when the ribbon shift is operated.

30. The combination of a typewriting machine having a ribbon shift, a typesetting machine, special sign characters carried in the typesetting machine, mechanism for releasing the same for assemblage with other matter, and a connection between the releasing mechanism for the special signs and the ribbon shift mechanism of the typewriter.

31. The combination with a computing machine having numeral keys and computing mechanism, a typewriting machine having a ribbon shift, a typesetting machine carrying numeral type and sign type, a printing member in which such type may be assembled, mechanism for causing the numeral keys of the computing mechanism to release corresponding numerals in the typesetting machine, and mechanism for causing the actuation of the ribbon shift of the typewriting machine to be accompanied by the release of one of the sign type of the typesetting machine, and means for assembling such numerals and sign type in the same line.

32. The combination of a computing machine of the type wherein a single set of digit keys is effective irrespective of the column in which the digit appears, and a composing machine having a set of numeral characters, and operating connections between the numeral keys of the computing machine and the numeral character mechanism of the composing machine.

33. The combination of a computing machine having computing mechanism and a set of ten keys for operating the ten digits irrespective of the column position of such digits and a typesetting machine having a type case containing type of the ten digits with ten individual actuators adapted to release the same, a set of ten contacts controlled by the computing machine, and ten circuits leading from such contacts to the composing machine actuators.

34. A computing machine of the type wherein the digit keys are actuated in the order in which the digits appear in the numeral to be added, combined with a composing machine of the type wherein the characters are caused to appear in the order of actuation, and means for simultaneously actuating the computing machine and the composing machine.

35. The combination of a computer of the type wherein the digit keys are actuated in the order in which the digits appear in the numeral to be added, a composer of the type wherein the characters are assembled in the order of actuation, and operating connections between the digit keys

of the computer and individual numeral actuators of the composer.	puting mechanism and assemble corresponding printing members in the composing mechanism.	
36. The combination of an adding machine, a typesetting machine, a type chase, an actuator common to the adding machine and typesetting machine, and means operated thereby for including numerals in the adding mechanism of the adding machine and for releasing corresponding numeral type of the typesetting machine and assembling the same in the type chase.	40. The combination of a computing machine, equipped with numeral keys, a typesetting machine and means whereby said numeral keys, while they are actuating the computing machine may also assemble corresponding type in the typesetting machine.	80
37. The combination of a Moon-Hopkins billing machine, a Set-O-Type typesetter, a multigraph railed segment, and a common numeral key-board actuator for the billing machine and typesetter operating the computing mechanism of the billing machine and the type discharge mechanism of the typesetting machine and causing the assemblage on the multigraph segment of the type discharged by the typesetter.	41. The combination with a computing machine having numeral keys to actuate it, a typesetting machine having a type case, mechanism for ejecting type therefrom and assembling it, and connecting mechanism between each of said numeral keys of the computing machine and the ejecting mechanism for the corresponding numeral in the typesetting machine, said keys simultaneously operating the computing machine and the ejecting mechanism of the composing machine.	85
20 38. The combination of a computing mechanism, a composing mechanism, and mechanism for simultaneously actuating both the computing mechanism and the composing mechanism.	42. The combination of a computing machine having numeral keys to actuate it, a composing machine having individual electrically operated elements corresponding to the different digit type, and a set of contacts in the computing machine actuated by the numeral keys thereof and each simultaneously controlling one of said elements of the computing machine.	90
25 39. The combination of a computing mechanism, a composing mechanism, a set of numeral keys and intermediate mechanisms between said keys and the computing mechanism and between said keys and the composing mechanism, whereby the same keys may simultaneously operate both mechanisms to add amounts on the com-	HAROLD H.
